UNITED STATES PATENT OFFICE.

HANS C. BEHR, OF SCARSDALE, NEW YORK.

MACHINE FOR SEPARATING LIQUIDS FROM SOLIDS.

Application filed July 24, 1922. Serial No. 577,130.

To all whom it may concern:

Be it known that I, HANS C. BEHR, a citizen of the United States, residing at Scarsdale, in the county of Westchester and State of New York, have invented certain new and useful Improvements in Machines for Separating Liquids from Solids; and I do hereby declare the following to be a full, clear, and exact description of the invention, such 10 as will enable others skilled in the art to which it appertains to make and use the same.

This invention relates to an apparatus for centrifugally separating liquids from solids, 15 and has for its object to improve the constructions heretofore proposed.

With these and other objects in view, the invention consists in the novel parts and combinations of parts constituting the apparatus, all as will be more fully hereinafter disclosed and particularly pointed out in the claims.

But it may be said that one particular object of the invention is to provide an apparatus of this nature provided with a horizontal axis or at least with a non-vertical axis, and such an assemblage of parts as will enable one to easily obtain access to the location of the bearings and gears in order 25 that their functioning and operation may be readily supervised and controlled.

Another object of the invention when more specifically stated, is to provide such a design of the apparatus as will facilitate the 30 assemblage, the dismantling, and the replacement of those parts which are most subject to wear.

Still other objects are to prevent the escape of the separated products from the receivers into which they are discharged except at the proper outlets that are provided, and to prevent any lubricant from entering 35 the material being treated.

These objects are accomplished by a construction which enables the material to be fed through a fixed tube, horizontally disposed. The material enters the center of a horizontally disposed or somewhat inclined continuous centrifugal machine. From this 40 centrifugal machine, the said separated solids and liquids are each discharged into narrow zones spaced apart, and are deflected from the plane of rotation preferably in such a manner as to recede from each other. The

separating elements are overhung at corresponding ends of their respective axes, the one located within the other and geared together, so that the inner axle carrying the conveying and discharging element rotates at a somewhat slower rate than the outer tube shaped axle carrying the foraminous separating element, all as will appear more fully hereinafter.

Referring to the accompanying drawings forming a part of this specification, in 45 which like numerals designate like parts in all the views:

Figure 1 is a vertical side elevational view, partly in section, through the center line portion of an apparatus made in accordance with this invention;

Figure 2 is a plan view, partly in section, of the parts shown in Figure 1, the sectional portions being shown on a plane through the central portion of the machine;

Figure 3 is an elevational view partially in section of certain of the parts shown in Figure 2, when looking toward the feed end of the apparatus or toward the left, as seen in said figure;

Figure 4 is an elevational view of the feed end of the apparatus when looking toward the right, as seen in Figure 2;

Figure 5 is a view of the conveyor when removed from the machine;

Figure 6 is a transverse sectional view taken through the impeller ring and smaller end of the foraminous screen;

Figure 7 is a detailed sectional view of the enlarged end of the foraminous screen surrounding the conveyor shown in Figure 5;

Figure 8 is an enlarged sectional view, showing a portion of the parts shown in Figure 2 for the sake of clearness; and

Figure 9 is an elevational view partly in section of those portions of the machine which surround the enlarged end of the foraminous screen when looking toward the feed end of the machine.

Referring more particularly to Figures 100 1 and 2, 1 represents the frame of the machine, provided with the bearings 2 and 3, within which revolves the quill 5, and also with the bearing 4, which carries the hub 6 of gear 7. Gear 7 is fixed on the small end 105 8 of shaft 9, by the feather 106 and nut 105. Shaft 9 is carried at its large end 31 by the bearing sleeve 10 fixed in the end 11 of

quill 5. Quill 5 has fixed on it the pulley 12, which is rotated by a belt not shown from any suitable source of power. The end 13 of quill 5 has fixed to it the gear 14, 5 which meshes with a gear 15 mounted on a shaft 16 carried in bearings 17 and 18, forming extensions respectively of bearings 3 and 4. Gear 15 is rigid with a gear 19, which meshes with a gear 7 fixed on shaft 9, 10 as previously described. Gear 15 is somewhat larger than gear 14 and gear 7 is larger by the same amount than gear 19, so that shaft 9 is compelled to rotate at a somewhat slower rate than quill 5. End 15 11 of quill 5 is integral with the disc 20, rigid with the conical foraminous mantle 21, having on its inner surface numerous grooves 22, at each of which said mantle is perforated with a large number of holes 23 20 as best shown in Figures 7 and 8. Overlying the inner surface of mantle 21 is the conical screen 24, held in place at its smaller end by inserting it in the circular groove 25. Referring also to the enlarged view, Figure 25 8, it is seen that the large end of screen 24 is bent outward into the groove 26 in the thickened end 29 of mantle 21, forming a narrow flange 27, through which it is secured by a filling ring 28, forced into said groove 26. The said filling ring 28 may be a piece 30 of rope, or square packing, or short pieces of wood, or any suitable material, which can be readily removed. During operation, the filling will be firmly held in place by centrifugal force. Holes 30, Fig. 8, permit the insertion of a rod for forcing out said filling 28.

The larger portion 31 of shaft 9 has formed on it the disc 32, integral with the 40 rim portion 33, the conical portion 34, and the cylindrical extension 35. Where the part 35 joins part 34, inner blades 116 are attached, their inner or horizontal edges forming a continuation of the bore of part 45 35 as best shown in Figure 8. From the center of disc 32 projects the boss 36, terminating in the cone 37 having the blades 38 on its surface. Rim 33, as best shown in Figures 2 and 8, is perforated with numerous holes 39, the solid parts 40 between them, see Figure 6, serving as impeller blades to impart velocity to the material fed to said holes. For the sake of cheapness of manufacture the spaces 39 between blades 40 are preferably made as round drilled holes, but their center lines need not pass through the axis of rotation of the rim 33.

Where the conical tube portion 34 joins 60 the rim 33 it has on its outside a cylindrical part 41 over which is fitted the annular end-plate 42 of the foraminous mantle or screw conveyor 43, see Figures 2, 5 and 8. The conical shell, or mantle 43, has fixed to its outer surface the helically disposed ribs 44,

surrounding the said mantle shell 43 like the threads of a screw and forming the conveying element for the material over the screen 24 from the small to the large end thereof. A number of turns or helices are 70 used on the conveyor 43, because a single helix would not make a perfectly balanced structure.

The inner periphery of end plate 42 is extended to form the conical inner shell 45 75 with a thickened cylindrical part 46. The end of the part 46 fits over the tubular member 35, which is threaded at its end and fitted with the nut 47, provided with a number of setscrews 48, as best shown in Figures 80 2 and 8.

The entire conveyor structure is secured by nut 47, which is screwed on by hand, after which the setscrews 48 are tightened with a small wrench. A dowel pin 200, 85 Figures 3, 2 and 8, prevents the conveyor structure from turning on the rim or ring 33. The particular method of fastening just described is adopted in order to avoid any distortion of the machine that would be 90 likely to occur if the ring nut 47 were screwed down too tight. The rapid and easy removal of conveyor 43 from the machine is also made possible by means of this method of fastening, because the parts can 95 be quickly loosened and removed, thus enabling the withdrawal of the said conveyor 43 and affording access to the separating screen 24 for overhauling and repairs.

The large end of conveyor 43 terminates 100 in an inwardly extending disc 49, and in the space between the discs 49 and 42 are fixed the fan blades 50, best shown in Figures 2 and 8, which by their rotation serve to force air, and in some cases liquid spray, 105 through the holes 51 in the foraminous mantle of conveyor 43, through the material treated on screen 24, through said screen and through the holes 23 in mantle 21, this said air thus escaping with the separated liquid. Air is admitted to the inner edges of fan blades 50 through the cylindrical shell 52, forming an outward extension from the inner periphery of disc 49. 110 Water, or other liquid or steam may also be admitted through a tube 53, see Figure 2, to be mixed with this said air by the blades 50 and driven through the material with it, as may be desirable in the separating process. 115

The material to be separated is introduced into the center of the machine through a tube 54, see Figures 1, 2 and 8, slightly expanded at the discharge end 55. Tube 54 issues from an elbow member 56, supported by arms 57 from the conical front plate 58, see Figures 1, 2 and 4. The supply of material comes through the flexible tube 59, attached to the other end of elbow 56. 120

So far as has now been disclosed, it will 130

be clear that through the train of gears 14, 15, 19 and 7, the mantle 21 will be more rapidly rotated than will be the mantle 43; that the mixed liquids and solids entering 5 through the tubes 59, 56, and 54, will find their way through the openings 39 to the space between said mantles 21 and 43, and that owing to the action of centrifugal force, aided by the air pressures caused by the fan 10 blades 50 and 116, as well as by other agencies to be disclosed below, the liquids will pass on through said mantle 21, while the solids will be rotated around the periphery of the cone shaped conveyor or mantle 43 between its screw threads 44, until they are discharged at the larger end of said mantle, all as will likewise appear more fully hereinafter.

But referring again to the mantle 21, at 20 the small end of said mantle inside of screen groove 25, blades 60 are fixed encircling the solid portions or blades 40, integral with disc 32, as best shown in Figures 2, 6 and 8. The said blades 60, owing to the reducing action of the gear train 14, 15, 19 and 7, will thus rotate at a greater number of revolutions than the blades 40, the purpose of which arrangement will appear further on.

30 On the outer surface of mantle 21, at its larger end, there is fixed the small end of conical shell 61, extending towards, but not to, the small end of mantle 21. To the said small end of mantle 21 is fixed the small end of shell 62, disposed parallel with mantle 21, but separated from it beyond its point of attachment by the space 63. The large end of shell 62 does not quite reach the vertical plane of the large end of shell 61, but 40 is separated therefrom by a small space 64, as appears from Figures 2 and 8.

After the liquid passes through the mantle 21 in the manner above described, it finds its way into the receiver 68 now to be disclosed, and which is shown detached from the machine in Figure 3. That is to say, surrounding the large end of shell 61, Figures 1, 2, 3 and 8, is the inner edge 65 of the stationary dished deflecting ring 66, the outward extension of which reaches somewhat beyond the vertical plane of the large end of shell 62. One edge of ring 66 is concavely curved, as at 67. The deflecting ring 66, is formed into an upper half or shell 69, and 55 a lower half 86, and these two halves constitute the said liquid receiver 68. The lower half 86 of ring 66 is joined to the plate 85, Figures 1 and 3, forming a downward extension of the semi-circular shell 69 or an exit 60 for the fluid. The portion of receiver 68 opposite plate 85, is closed off by a flat plate 70, Figures 1 and 3, having a circular central opening 71, Figures 1 and 8, and from the edge of which there extends into the receiver 68 the cylindrical shell 72 with an

annular disc 73 at its free end, thus forming an outward circular channel around said shell 72. The outer face of disc 73 is so located that the large end of shell 62 projects slightly beyond it, as shown in Figures 1, 2 and 8.

From Figure 3 it will be seen that the upper face 75 of the receiver 68 is made semi-circular while the lower face 76 is made rectangular and without a base, thus providing a large opening 121 for draining off the liquid thrown into said receiver. An air escape 74 is provided at the top of the upper part to give additional chance for the escape of air driven through the material by the fan blades 50. As will be seen from Figure 3, the upper parts 75 and 69 of the receiver 68 are connected to the lower parts 76 and 86 by bolts 77 passing through suitable flanges 78 and 79 at the plane of junction.

85 The special construction just described facilitates the lifting out of the rotating parts of the machine by first removing the upper parts 75 and 69 of the receiver. The lower portions 76 and 86 of the receiver with plate 90 70 are fixed to the front plate 81 of the main frame 1 by the bolts 80, as shown in Figure 1.

It will now be clear that by removing the bolts 98, the front plate 58, and the nut like ring 47 the whole inner cone shaped mantle 95 43 may be readily slid out of the machine over the straight guide pins 200, and by removing the bolts 77, Figure 3, the upper portion of the liquid receiver 68 can be lifted off to expose the mantle 21 and its associated 100 parts.

105 Encircling the thickened large end 29 of mantle 21, Figures 1, 2 and 8, but located slightly back of the vertical plane of its face, is the inner edge 82 of the dished deflecting ring member 83, forming the back of the receiver 84 for the separated solids. This said receiver is shown removed from the machine in Figure 9, the view being taken when looking from the rear toward 110 the feed end of the machine. The said ring 83 is joined to the semi-circular shell 87, Figures 2, 8 and 9, and to plate 88, see Figures 1 and 9. Plate 88 is in turn joined at its ends to the vertical sides 89 of receiver 115 84, see Figures 1 and 9. Said plate 88 and sides 89 form downward continuations of the semi-circular shell 87 enclosing the upper half of the receiver 84, as will be clear from the drawings. The front of receiver 84 is formed by a flat plate 90, Figures 1, 2, 4 and 8. The entire bottom 201 of receiver 84 is left open for the escape of the dried solids. The plate 88 has two braced feet 91, with which it is secured by bolts 92 to base 120 93, connected by lateral ribs 94, Figure 1, with the main frame 1.

125 When it becomes necessary for any reason to remove the rotating parts of the machine, receiver 84 may be also removed bodily after

merely unscrewing bolts 92, when the upper part of the liquid receiver 68 is lifted off, as previously explained. An air vent 95 is provided at the top of the receiver 84 to afford an escape for any air that may come over with the dried solids, or enter through the annular openings 82 and 102, constituting the dividing spaces between the rotating and stationary parts. Front plate 90 has a large circular central opening 96, figures 1, 2 and 8, into which is fitted the inwardly coned ring 58 before described, and which is made removable, being secured to end plate 90 by bolts 98 passing through flange 97.

15 It will be seen from Figures 1, 2 and 8 that the large ends of shells 61 and 62 are respectively provided on their exteriors with short teeth-like fan blades 99 and 100, blades 99 rotating within the inner edge 65 of deflecting plate 66, and blades 100 similarly rotating within the annular disc 73 at the end of cylindrical shell 72. The said blades are inclined as shown in Figure 1 so that they pick up air from the outside with their advancing edges. The said blades thus tend to force a current of air into the liquid receiver 68, and thereby counteract any tendency of liquid or air carrying liquid to escape from said receiver at the joints where it is closed by the rotating elements.

Similar short inclined fan blades 101 are provided on the periphery of the end 29 of mantle 21 to rotate within the inner edge 82 of the solids deflector 83, for the purpose of creating an inward air current to prevent any stray particles of solids from escaping at the joint formed. For the same reason the rotating shell or air duct 52 has at its end short peripheral blades 102, higher at their inner edge and adapted to rotate within the inner edge of the conical ring 58.

It will now be clear that in addition to the action of centrifugal forces and the actions of the fan blades 50 and 116 herefore mentioned as aiding the separation of the liquids from the solids, this machine invokes the assistance of the sets of fan blades lettered 40, 60, 99, 100, 101, 102, some of which served in a measure to force air along with the liquids from the orifices 22 of mantle 21.

At the shoulder 103, Figure 2, where shaft 9 is reduced in diameter to form the part 8, a collar 104 is fixed by clamping against said shoulder 103 the gear 7. This clamping action is effected by means of the nut 105. Collar 104 is prevented from rotating on shaft 8 by feather 106. Collar 104 is encircled by the ring member 107, integral with gear 14, and to the face of ring 107 is attached the annular disc 108 by means of screws 109. Collar 104 is thus free to rotate in the space enclosed by gear 14, ring member 107 and disc 108, and acts as a thrust-bearing to prevent any axial displacement

between shaft 9 and quill 5 and of the associated parts.

The collar or bearing 10 is only subject to radial loads, and these will not be much more than those due to the weight of parts attached to shaft 9. Therefore, and also because of the slow relative rotation of shaft 9 inside of quill 5, bearing 10 will require only a slight amount of lubrication, and if anti-friction metal is used, no lubrication whatever will be required. This feature is important, from a practical point of view, because it is objectionable with most materials treated to have them contaminated with oil. To insure that no oil can pass from the copiously lubricated thrust collar 104 to the material in space 111 between the mantle 43 and fan blades 60, or through the clearance space 140 between the shaft 9 and guide 5, nor between the bearing 10 and the clearance spaces 114, 115, a sufficiently deep outward groove 150 is provided at the junction of spaces 114 and 115 for such oil to gather in, and a number of holes 151 lead outward therefrom, by which said oil is thrown off centrifugally during the operation, and thus permitted to drain off when the machine is not running.

The operation of the process and apparatus, so far as has been now disclosed, is as follows:

Power being applied to the pulley 12 by a suitable belt not shown, the quill 5 with attached disc 20 and mantle 21 are revolved at the separator end of the machine, while gear 14 is coincidentally revolved at the gear end of the machine. Gear 14 in turn revolves gear 15 with the attached gear 19, and gear 19 revolves gear 7 with shaft 9 and the attached conveyor mantle 43 at the separator end. The rotation of mantle 43 will be in the same direction as that of quill 5 and mantle 21, but at a somewhat slower rate due to the proportions of the gear train 14, 15, 19 and 7. At the same time, material is continuously supplied at a uniform rate through hose 59, elbow 56 and feed tube 54. Before issuing at the widened mouth 55 of the fixed tube 54 the blades 38, rotating at a high speed with shaft 9, impart a whirling motion to the material, by which it is made to issue in an annular spreading jet of approximately uniform thickness from the mouth 55. The rotating blades 38 or their equivalent are important in a machine having a horizontal or somewhat inclined axis, like that of the present invention, because without them the material would be liable to pour out, chiefly on the lower side of the mouth 55, and would not be evenly distributed to the inner edges of the impeller blades 40 and to the screen 24, thus causing an uneven loading and an unbalancing of the machine. But the blades 38 may be omitted where there is sufficient friction be-

tween the material and the cone 37 to impart adequate rotary motion to said material.

The material issuing from the mouth 55 in a more or less radial direction will be caught partly by the blades 116 and partly by the inner smooth surface of cone 34, integral with said blades. Both these members on account of their diameters being 10 larger than that of blades 38, have a higher velocity than the outer edges of blades 38 for the same number of revolutions, which they must make by virtue of their integral construction, and this higher velocity tends 15 to equalize the thickness of the material layer. Material caught by blades 116 will also be driven onto the inner surface of cone 34, and together with the material directly delivered thereon, will be driven by 20 centrifugal force to the large end of said cone 34. At the same time, and since the inner surface of cone 34 is necessarily truly centered from the axis of rotation, if there exists at any plane of rotation a difference 25 in the thickness of material on said true inner surface, the hydrostatic pressure due to such difference in thickness under the action of centrifugal force will cause an equalizing of such thickness, in a similar manner to 30 that in which liquids on a planet will be leveled up to a truly central circle in the plane of rotation under the action of gravitation. From the foregoing, it is obvious that the material will be distributed to the 35 inner edges of all the impeller blades 40 in practically equal amounts. The provision for such equal distribution of the material is a very important one with a machine of this character having its axis horizontal, or 40 somewhat inclined from the horizontal.

The blades 116 on the inside of the small end of cone 34 also have the function of creating a current of air into the space within cone 34 and ring 33, as above stated, 45 and of preventing outward leakage of any stray particles of material.

The material delivered to the inner edges of blades 40, as described, is further accelerated by them and moved outward by 50 centrifugal force, attaining the velocity of the outer circumference of blades 40. At this point the material is delivered to the inner edges of blades 60, which through the disc 20 and quill 5 are integral with gear 55 14, rotating as previously explained at a greater number of revolutions per minute, than gear 7, to which blades 40 are rigidly connected through disc 32 and shaft 9. The inner edges of blades 60 thus having a 60 greater velocity than the outer edges of blades 40, the material will be quickly removed at the circumference of blades 40, thus preventing an accumulation of said material in the said space 111 and the building up of pressure within it, which pressure

would tend to force the mantle conveyor 43 out of the mantle 21, and would therefore fall onto the thrust bearing 104 with the possibility of overloading it.

The blades 60 could be omitted in those 70 cases where the frictional contact of the material with the curved surface 112, see Figure 2, at the small end of mantle 21, is sufficient to bring the material up to the speed of said surface. The forward curvature of the surface 112, either with or without the blades 60, causes the material to acquire a forward motion towards the space 118 between mantle conveyor 43 and mantle 21, occupied by the conveyor helices 44. 80 These said helices now pick it up and screw the material forward in an axial direction along the surface of screen 24, during which process the liquid content of the material is driven outward by centrifugal action and 85 air pressure through the screen 24 and into the grooves 22, escaping from these grooves outward through the holes 23. The screw like action of the conveyor ribs 44 is due to their speed being slower than that of the material carried along by friction with the faster rotating surface of screen 24. During the process just described air is being drawn into the interior of conveyor cone 43 by the action of the fan blades 50, which drive it outward through the holes 51 in said cone 43 into the space 118, whence it is driven outward with the liquid through the screen 24 and holes 23 in 90 mantle 21, the air aiding the cleaning process by brushing or blowing off liquid films adhering to the solid grains of the material. To further aid the cleaning action, water or other liquid, or steam, may be introduced 95 through the pipe 53 as above mentioned, to the inner edges of blades 50, which latter atomize said liquid and cause it to mix intimately with the air drawn in and discharging the same with the air in the direction described. 100

Owing to the inclination of the conical surface of screen 24, centrifugal force will aid the conveyor helices 44 in moving the material towards the large end of said screen, but the inclination of said screen that is admissible by other considerations is such that it is found that the frictional resistance of most materials in moving over the screen surface will generally overbalance any aid to forward movement that can be derived from centrifugal action. This excess of frictional resistance will therefore tend to force the mantle conveyor 43 with its attached parts towards the small 115 end of the mantle 21, thus tending, through shaft 9, to press thrust collar 104 against the disc 108, attached to gear 14. It is found, however, that the amount of this pressure on the thrust bearing or collar 120 104 will not be great as compared with the 125 130

pressure, which might be produced on said bearing in the opposite direction in case a centrifugal pressure were set up in the material while passing through the space 111, as previously described.

The liquid discharged through screen 24 and holes 23, in flying off outward, meets the inner conical surfaces of shells 61 and 62, except at the narrow space 64 between 10 the large ends of said shells. Driven by centrifugal action towards and off the opposed large ends of shells 61 and 62, these two bodies of liquid and air join with the part discharged at space 64 and fly off 15 against the inclined face of the deflecting ring 66, where part of the liquid and all the air flies off laterally from ring 66, while some of the liquid will flow outward along ring 66 and around the curve 67, flying off 20 laterally at the edge 119. The large amount of frictional resistance during this process aids considerably in destroying the energy existing in the discharged mass of liquid and expanding air. The laterally 25 deflected liquid strikes against the opposite face of plate 70 of the liquid receiver 68, and at the same time allows the air mixed with it to separate out and gather in the space 120, whence it can escape outward 30 through air vent 74 and also at the open bottom 121. The liquid deflected from plate 66 and discharged from edge 119 has some tangential velocity, when it strikes against plate 70. Hence the impact on 35 plate 70 is not vertical to its surface, but somewhat inclined, and the liquid therefore is less scattered and tends to flow along and hug the surface of plate 70, so that the friction generated destroys most of the 40 energy of motion remaining in said liquid. Most of the liquid therefore flows downward and out at the open base 121. That part of the liquid flowing down plate 70 in the space 122 above the circular shell 45 72 is found to be diverted sideways over its surface and finally drips off at its lower part through the open bottom 121.

In order to prevent any of the agitated mixture of liquid and air scattered around 50 in receiver 68 from escaping outward at the narrow annular openings 123 and 124, where the rings 66 and 73 approach the rotating shells 61 and 62, see Figure 2, an inward current of air is produced by the short 55 inclined fan blades 99 and 100, attached to the said shells 61 and 62, such air escaping from the receiver 68 through vent 74 and open bottom 121.

The separated liquid will generally contain 60 small particles of solid matter, which may gradually bank up on the high part of shell 72, from where it may be periodically dislodged by an attendant through vent 74, or if gathering in sufficient quantity, it may be continuously removed by any

suitable means such as an air jet from a pipe extending through vent 74, as at 130 in Figure 3.

The two conical shells 61 and 62 are preferably provided instead of a simpler construction involving a single shell covering the entire liquid discharge zone from mantle 21, for several reasons. One of these reasons resides in the fact that by the use of two shells the plane of discharge 75 64 can be located at the most convenient point along the axis of the machine. Furthermore, since an inner conical surface like that afforded by shells 61 and 62 will through surface friction bring the thin layer 80 of liquid coming in contact with it practically up to its own velocity, such shells increase the energy of motion of the liquid, while the power required for this is in proportion to the square of the diameters of 85 their large ends. Therefore, since the bulk of the liquid will generally be discharged from screen 24 close to its small end, and a comparatively small amount nearer its large end, it would cause an unnecessary 90 increase of power consumption and whirling of the liquid, if the latter were all delivered from screen 24 into a single rotating shell. In this latter case, it is found that the large diameter of the single shell would 95 have to be even larger than the large diameter of shell 61.

The solid particles of the material moved over screen 24 towards its large end arrive 100 there deprived of liquid and are discharged over the face of end 29 of mantle 21 in a thin sheet, the particles taking a course tangential to the diameter at discharge and striking onto deflecting ring 83, are thereby 105 diverted laterally with some loss of energy of motion and impinge on the opposite face of plate 90, whence part of them may be thrown back and forth until their energy is exhausted. These particles discharged below the rotating air inlet shell 52 will then 110 drop directly downward and escape at the open bottom 201 of the solids receiver 84. Of the particles discharged in the space above shell 52 some will drop directly onto the latter and some onto the conical ring 58, partly sliding along its surface onto shell 52 and partly sliding off sideways and dropping down through the opening 201. The particles falling onto the rotating shell 52 115 will be partly thrown off by centrifugal force and will partly slide off, all finding 120 their way to and through the open bottom 201.

At the same time the short inclined fan blades 101 at the end 29 of mantle 21 will 125 force currents of air through the annular space between the rotating parts and the inner edges of the stationary parts, and blow back any particles of solids that may tend to escape outward at these points. The 130

air thus supplied will escape partly at vent 95 at the top or through the open bottom 201. In a similar manner, and for the same purpose, a current of air produced by 5 blades 102 at the end of the rotating air duct 52 will prevent escape of solid particles at that point.

The illustrations herewith given show a machine with horizontal axis. It is obvious, however, that the axis of this machine may without detriment to its successful working, be somewhat inclined forward or backward, which might be desirable with some materials, in order to improve discharge conditions of either the liquid or solids products into their respective receivers. Such inclinations of the axis of rotation with this design of machine must, however, not exceed the limits beyond which 15 either of the separated products would fail to slide down by gravity over the inside surfaces of the members 66, 70, 83 or 90 of the products receivers. The horizontal disposition of the axis would always be preferred, and an inclined axis would be only adopted when other considerations outweighed the advantages of said horizontal axis.

As stated above, an important feature of 30 this invention resides in the readiness with which the parts can be removed for cleaning and repairs. So it is repeated that when it becomes necessary to examine or replace screen 24, it is only necessary to proceed as 35 follows: The conical ring 58 supporting the feed tube 54 is removed with the latter after unscrewing the bolts 98. Said removal is effected without breaking the feed connection 59, since the latter is flexible and of 40 sufficient length to admit of this. The set screws 48 in nut 47 are then loosened, so that the said nut can be unscrewed by hand, after which the conveyor with its attached parts is withdrawn, thereby exposing screen 45 24. The removal of screen 24 can be effected after pushing out the filling 28 from groove 26 by means of a rod inserted through holes 30 in the mantle end 29. To put in a new screen its small end is inserted into the 50 groove 25 at the small end of the inner surface of mantle 21. The edge at the large end is then bent over into the groove 26 at the large end and the filling 28 is forced in. The large end of the screen may also 55 have its edge bent over previous to insertion, in case it has an open joint lengthwise. The mantle conveyor 43 is then replaced, nut 47 screwed on by hand and set screws 48 tightened with a small wrench. Next the conical 60 ring 58 is put back and secured by bolts 98. The machine can then be started up and the supply of material turned on.

The same centrifugal machine is generally called upon to treat material that varies 65 from time to time in degree of separability.

Thus, a certain lot of material may be satisfactorily separated in a given centrifugal of the type described during its passage over the screen in the time fixed by the inclination and speed of the conveyor blades 70 44, but another lot of material may require a longer time or a shorter time for satisfactory separation. This can readily be provided for in this machine by having on hand a number of conveyor members 43 with 75 blades 44 of different pitches, to suit a longer or shorter time of treatment at the same rotary speed of the machine. It results that the change from one conveyor to another having a different pitch of screw 80 can according to the foregoing disclosure be readily and quickly made, and that therefore widely differing materials can be treated in the same machine after a slight alteration.

Most of the centrifugals proposed or tried for the continuous separating of liquids from solids have been arranged with a vertical axis, following in this respect the well known intermittently operating type of centrifugal. But in the continuously operating 90 machines with vertical axes, the products of separation are diverted downwards by gravity in the direction of the axis, and the separator part is located above the axis with its bearings and an attachment to a motor. 95 These parts are all very inaccessible, on account of their being of necessity entirely or almost entirely enshrouded by the two products discharged. If a belt drive is used, this will have to pass through a closed passage 100 penetrating the said discharge products.

In an intermittently operating centrifugal machine having a vertical axis, there are generally not more than two bearings and these on account of their intermittent 105 operation do not call for the care and attention necessary with the large number of bearings required in a continuously operating centrifugal, which in some industries, like sugar refining, may have to run night 110 and day for six days every week during nine months of the year. Continuous centrifugals will nearly always be of a much smaller diameter than intermittent ones, because for the same peripheral speed the centrifugal acceleration, of which a maximum is desirable, varies inversely as the diameter. Hence continuous centrifugals 115 would run at twice or three times the rate of revolutions of the intermittent ones, which feature makes attention to their bearings still more important. Intermittently operating centrifugals have, on account of the frequent stops for charging 120 and discharging, very much less capacity of output than continuous ones, and to make up for this defect to some extent at least and to decrease the cost of attendance they are made of a larger size, thereby losing considerable centrifugal effect. 130

If the shaft and bearings are placed above the separator part in a vertical continuous machine, great difficulties are encountered in designing for the introduction 5 of the material, and of the air and other substances that may be required in its treatment. Such an arrangement would also require a more extensive dismantling, and hence would take more time and labor to 10 replace the short lived screens and other parts subject to wear by the movement of material incident to a continuous process. Since the high speed bearings and gears demand ample lubrication, it will be next 15 to impossible to keep oil from finding its way down into the separator and mixing with the material treated, which is inadmissible in most cases.

Direct connected motors are awkward to 20 apply in a continuous centrifugal, so that a laterally disposed belt drive would generally be adopted. This would require much more floor space with the vertical axis, than with a horizontal, or moderately inclined 25 one, in which the belt would generally be carried either upward or downward from the source of power.

In the vertical machine the products of separation are necessarily diverted downwards by gravity, the discharge of the products being superimposed around the entire circumference. This circumstance admits of only a moderate inclination of the axis from the vertical, assuming such inclination offered any advantage. Inclining the axis of the vertical machine does therefore not produce the same result as does an inclination of the axis in the horizontal type of machine, made the subject of this invention, and within the limits defined in the foregoing. In other words, the non-vertical centrifugal machine forming the subject of this invention is adapted to be placed with the axis either horizontal or 40 moderately inclined, and with the separator parts overhung at one end of said axis with the result that it is free from the objections mentioned as pertaining to the vertical type.

It will now be clear from the foregoing 50 description that the present invention provides for a process of operation with a horizontal type of continuous centrifugal separator, in which the material treated is introduced in a uniformly distributed manner to the inside of the accelerating member, thereby maintaining the machine in balance during operation, and operating at a maximum capacity under existing conditions; 55 that pressure in an axial direction tending to force apart the conveying and separating members, is counteracted by a secondary accelerating member, surrounding the first named accelerating member; that the separated materials are discharged outward

in zones separated from each other by a considerable distance in an axial direction; that escape of products from their receivers at undesirable places is prevented by inward currents of air; that proper means of escape from said receivers is provided for the air used in the separating process; that the apparatus is arranged for easy inspection, cleaning, and repairing, of all its parts; that oil is prevented from reaching the material treated; that the removal and replacement of parts subject to wear, and the dismantling of the machine generally as for inspection, can be easily and rapidly effected; and that the type of horizontal machine herein described may also be operated in a position inclined within the limits herein set forth.

It is obvious that those skilled in the art 85 may readily make modifications of the devices herein disclosed. I therefore do not confine myself to the particular design shown and described, except as may be required by the claims.

What is claimed is:

1. In a centrifugal machine of the continuous horizontal type adapted to separate liquids from solids, the combination of a pair of concentrically disposed cone shaped foraminous mantles spaced apart; a substantially horizontal shaft about the axis of which said cones revolve; means for continuously rotating said cones at different speeds, about said axis, as a center; means for continuously feeding material to said cones while rotating; means associated with said shaft for causing said material to be evenly distributed to the space between said cones; a pair of oppositely disposed cones of different diameters spaced apart provided with rims, and carried by the outer one of said first named cones and adapted to catch a portion of the liquid passing through said outer cone; and a pair of receivers associated with said rims and provided with stationary ring-like edges in which said rims rotate.

2. In a centrifugal machine of the horizontal type, the combination of a pair of separated foraminous, concentrically disposed cones; means for feeding material in a direction from the larger ends of said cones to the smaller ends thereof and to the space between said cones; a third cone provided with a rim carried by the outermost of said pair of cones and adapted to catch a portion of any liquid that may pass through said outermost cone; means for rotating the cones of said pair at different speeds; a conveying helix carried by the innermost cone of said pair; a receiver for liquid associated with said outermost cone provided with a ring like edge in which said rim rotates; and a receiver for solids into which said helix is adapted to deliver.

3. In a continuously operating centrifu-

gal machine of the horizontal type, the combination of a pair of separated foraminous, concentrically disposed cones; means for feeding material in a direction from the 5 larger ends of said cones to the smaller ends thereof and to the space between said cones; a third cone provided with a rim carried by the outermost of said pair of cones adapted to catch a portion of any liquid that may 10 pass through said outermost cone; means for rotating the cones of said pair at different speeds; a conveying helix carried by the innermost cone of said pair; a receiver for solids into which said helix is adapted 15 to deliver, provided with walls at such an inclination to the horizontal as will insure said solids passing over the same under the action of gravity; and a receiver for liquids into which said third cone is adapted to 20 deliver, said receiver also provided with a ring like edge in which said rim rotates.

4. In a centrifugal machine of the horizontal type, the combination of a pair of separated foraminous, concentrically disposed cones; a third cone provided with a rim, carried by the outermost of said pair of cones and adapted to catch a portion of any liquid that may pass through said outermost cone; means for rotating the cones of 25 said pair at different speeds; a conveying helix carried by the innermost cone of said pair; means disposed axially of said cones for feeding material to be treated from the larger ends to the smaller ends of said cones 30 and to the space between said pair of cones; means for causing said material to be uniformly distributed in said space; a receiver for liquid associated with said outermost cone, said receiver also provided with a ring like edge in which said rim rotates; and a receiver for solids into which said helix is adapted to deliver.

5. In a continuously operating centrifugal machine of the horizontal type, the combination of a pair of separated concentrically disposed foraminous mantles, circular in cross-section; a pair of members each provided with a rim circular in cross section and carried by the outermost mantle 45 of said pair of mantles said member adapted to receive a portion of any liquid passing through said outermost mantle; a liquid receiver provided with ring like edges in which said rims rotate and adapted to receive liquid from said pair of members; a screw conveyor carried by the innermost of said pair of mantles; a receiver for solids into which said screw conveyor is adapted to deliver; axially disposed means extending 50 entirely through the lengths of said mantles for feeding material to the space between said pair of mantles; and means by which the innermost of said mantles may be readily removed for replacements or repairs and replaced in the machine.

6. In a continuously operating centrifugal machine of the horizontal type, the combination of a pair of separated, concentrically disposed foraminous mantles circular in cross section; a pair of members each 70 provided with a rim circular in cross section and carried by the outermost mantle of said pair of mantles, said members adapted to receive a portion of any liquid passing through said outermost mantle; a liquid receiver provided with ring like edges in which said rims rotate and adapted to receive liquid from said pair of members; means by which a portion of said receiver may be readily removed from the machine 75 to afford access to said outermost mantle; a screw conveyor carried by the innermost of said pair of mantles; a receiver for solids into which said screw conveyor is adapted to deliver; means by which a portion of said last named receiver may be removed to afford access to said outermost mantle; and means by which the innermost 80 of said mantles may be readily removed for replacements or repairs and replaced in the 85 machine.

7. In a continuously operating centrifugal machine of the horizontal type, the combination of a pair of separated, concentrically disposed foraminous mantles circular in cross section; a pair of members circular in cross section carried by the outermost mantle of said pair of mantles adapted to receive a portion of any liquid passing through said outermost mantle; a liquid receiver 90 adapted to receive liquid from said pair of members; blades for blowing air through said pair of mantles; a screw conveyor carried by the innermost of said pair of mantles; a receiver for solids into which said screw conveyor is adapted to deliver; means to feed material between said mantles; fan blades for impelling air along with said material as it is forced into the space between said mantles; and means by which the innermost of said mantles may be readily removed for replacements or repairs and replaced in the machine, substantially as described.

8. In a continuously operating centrifugal machine of the horizontal type, the combination of a pair of separated concentrically disposed foraminous mantles the outermost one provided with a set of fan blades on its outer surface and the innermost one 110 provided with fan blades on its inner surface; a pair of imperforate vessels on the outer surface of said outermost mantle adapted to receive a portion of the liquid passing through said last named mantle; fan blades carried by each of said vessels; a liquid receiver having an opening surrounding the fan blades of one of said vessels; and a receiver for solids having an opening surrounding the fan blades of the 120 125 130

other of said vessels, substantially as described.

9. In a continuously operating centrifugal machine of the horizontal type, the combination of a pair of separated concentrically disposed cone shaped foraminous mantles, the outermost one provided with a set of fan blades on its outer surface and the innermost one provided with fan blades on its inner surface; a pair of imperforate cone shaped vessels on the outer surface of said outermost mantle adapted to receive a portion of the liquid passing through said last named mantle; fan blades carried by each of said vessels; a liquid receiver a portion of which is readily removable from the machine having an opening surrounding the fan blades of one of said vessels; and a receiver for solids a portion of which is also readily removable from the machine having an opening surrounding the fan blades of the other of said vessels, substantially as described.

10. In a continuously operating centrifugal machine of the horizontal type, the combination of a pair of separated concentrically disposed foraminous mantles, the outermost one provided with a set of fan blades on its outer surface and the innermost one provided with fan blades on its inner surface; a fixed centrally disposed feed tube for passing material into the machine and having a flaring delivering end; a substantially horizontally disposed shaft around the axis of which said mantles revolve provided with impeller members coacting with said flaring end to evenly distribute the material between said mantles; a pair of imperforate vessels on the outer surface of said outermost mantle adapted to receive a portion of the liquid passing through said last named mantle; fan blades carried by each of said vessels; a liquid receiver having an opening surrounding the fan blades of one of said vessels, and a receiver for solids having an opening surrounding the fan blades of the other of said vessels, substantially as described.

11. In a continuously operating centrifugal machine of the horizontal type, the combination of an outer foraminous cone shaped mantle; a pair of cone shaped liquid receiving vessels each provided with a rim, said vessels spaced apart, and carried on the outer surface of said foraminous mantle, a liquid receiver provided with a pair of ring like stationary edges in which said rims rotate, said receiver adapted to receive liquid from said vessels; an inner cone shaped mantle concentrically disposed within and spaced from said first named mantle; a helical conveying means carried by said inner mantle; means by which material may be continuously fed to the space between said mantles; and means by which

said inner mantle may be readily withdrawn from the machine and a new one substituted.

12. In an apparatus for continuously separating liquid from solids by centrifugal action of the type herein described adapted to have its axis inclined at any angle between and including a horizontal position and an inclination for which any part of the separated products will not slide or flow down by gravity on a plane at right angles to said axis, the combination of a pair of cone shaped foraminous mantles and a fixed centrally disposed feeding means extending entirely through said mantles and communicating with the space between the same, said means comprising a fixed central feed tube for the material; a rotating tube surrounding said feed tube carrying means for impelling said material outward; and blades within an enlarged part of said rotating tube, to cause an inward current of air in the space between said feed tube and said rotating tube, thereby preventing material from escaping outward through said space.

13. In a non-vertical horizontal type apparatus for continuously separating liquids from solids by centrifugal action, the combination of a fixed central feed tube for the material; a rotating tube surrounding said feed tube carrying means for impelling said material outward; and blades within an enlarged part of said rotating tube, to cause an inward current of air in the space between said feed tube and said rotating tube, thereby preventing material from escaping outward through said space; an inner rotating conical surface to equalize the distribution of said material; a secondary means, rotating at a higher rate, to further accelerate said material; a foraminous body of rotation, rigid with said secondary means to receive the accelerated material at one end; and a screw conveyor, integral with said inner conical surface, to move said material over said foraminous body to expel the liquid therefrom by centrifugal action.

14. In an apparatus of the character described for continuously separating liquids from solids by centrifugal action, the combination of a fixed central feed tube for the material; a rotating bladed surface to whirl and spread the said material issuing from the mouth of said tube; an inner conical surface, integral with but outside said bladed surface, to receive and further spread and equalize the said material; a ring of rotating impeller blades to accelerate said material; a foraminous surface, rotating at a higher rate of speed to receive said material at one end; and a screw conveyor rotating at a lower rate of speed to move said material over said foraminous

surface to expel the liquid therefrom by centrifugal force.

15. In an apparatus of the character described for continuously separating liquid

5 from solids by centrifugal action, the combination of a fixed central feed tube for the material; a rotating tube surrounding said feed tube carrying means for impelling said material outward; and blades within an 10 enlarged part of said rotating tube, to cause an inward current of air in the space between said feed tube and said rotating tube, thereby preventing material from escaping outward through said space.

15 16. In an apparatus of the character described for continuously separating liquid from solids, the combination of an outer rotating foraminous mantle; a plurality of conical shells exterior to and integral with 20 said mantle to confine the outward liquid discharge to a narrow zone; a second foraminous mantle rotating inside said outer mantle; feeding means comprising a fixed central feed tube for the material; a rotating tube surrounding said feed tube carrying means for impelling said material outward; and blades within an enlarged part of said rotating tube, to cause an inward current of air in the space between 25 said feed tube and said rotating tube, thereby preventing material from escaping outward through said space, said feeding means connected with the space between said mantles for continuously conveying 30 material to said space; and a liquid receiver having a curved surface adapted to divert said zonal discharge against an opposite surface of said receiver to reduce the commotion in the discharged liquid by fluid friction.

17. In an apparatus of the character described for continuously separating liquid from solids by centrifugal action, the combination of a rotating foraminous mantle, 45 rigid with an exterior conical shell; a stationary liquid receiver surrounding said shell; fan blades rigid with said mantle and said shell adapted to force air into said receiver, and thereby to prevent outward 50 escape of liquid through the space between said receiver and the rotating parts.

18. In an apparatus of the character described for continuously separating liquids from solids, the combination of an outer rotating foraminous mantle; a more slowly rotating conveyor disposed inside said mantle and provided with an end ring portion and an inner tubular part; a shaft expanded at one end into a circular plate carrying a tubular 60 extension, over which said inner tubular part of said conveyor is removably fitted; a nut screwed onto the free end of said tubular extension of said shaft; and set screws passing through said nut against the end face 65 of said inner tubular part of said conveyor,

to force said disc against said part, thereby securing said conveyor in place while providing for its easy detachment from said shaft.

19. In an apparatus of the character described for continuously separating liquids from solids by centrifugal action, the combination of a rotating foraminous mantle; a disc rigid with one end of said mantle; a tubular shaft rigid with said disc; a screw conveyor; means for rotating said conveyor at a slower rate of speed than said mantle, comprising a shaft and a disc integral with said shaft; a bearing in one end of said tubular shaft to support one end of said second named shaft; a bearing to support the other end of said second named shaft beyond the other end of said tubular shaft; a collar, fixed to said second named shaft, adapted to bear with one face against the free end of said tubular shaft; a ring rigid with said tubular shaft surrounding said collar; and an annular disc, fixed to the face of said ring adapted to bear against the face of said collar.

20. In an apparatus of the character described, for continuously separating liquid from solids by centrifugal action, the combination of an outer foraminous rotating mantle, within which liquid is expelled from the material; a disc rigidly connecting one end of said mantle with one end of a quill carried in suitable bearings; a screw conveyor, rotating at a lower rate within said mantle, and rigid at one end through a circular plate with a shaft rotating within said quill; a bearing within said quill for supporting said shaft centrally; a circular oil-gathering groove associated with said disc and quill; and holes leading outward from 95 said groove to divert and carry off to the outside oil leaking from said bearing and thus prevent its getting mixed with the material treated.

21. In an apparatus of the character described the combination of a foraminous means provided with a rim like portion and adapted to separate liquids from solids; a receiver provided with a stationary ring like member in which said rim portion rotates; 115 and means carried by said rim like portion adapted to continuously cause air to flow between said rotating rim like portion and said stationary ring like member into said receiver when said foraminous means is functioning, whereby material delivered to said receiver is prevented from escaping therefrom.

22. In an apparatus of the character described the combination of a foraminous means provided with a pair of rotating means and adapted to separate liquids from solids; a pair of receivers associated with said rims and provided with stationary ring like edges in which said rims rotate; and 125 130

fan like means operated by said rims and adapted to force air into said receivers and prevent the escape therefrom of material delivered thereto.

- 5 23. In an apparatus of the character described the combination of a pair of foraminous cone shaped members placed one within the other, the outer member provided with a plurality of rings of rotating fan blades; a plurality of receivers associated with said cone shaped members provided with stationary ring like edges in which said fan blades rotate to force air into said receivers.
- 10 24. In an apparatus of the class described the combination of a rotating foraminous means adapted to separate solids from liquids and comprising a cone shaped member; a pair of open ended oppositely disposed cone shaped shells associated with said member providing a space between their larger open
- 15
- 20

ends through which liquid may pass in the form of a ring; rims provided with fan blades carried by said shells; and ring like means in which said fan blades rotate adapted to prevent said liquid escaping over said rims.

25 25. In an apparatus of the class described the combination of a rotating foraminous cone provided on its outer surface with a pair of cone shaped shells closed at their outer ends and providing a space between their inner open ends adapted for the passage of liquid; a receiver into which said liquid passes from said space; rims provided with fan blades carried by said shells; and ring like means carried by said receiver in which said fan blades rotate, whereby liquid delivered from said shells into said receiver is prevented from escaping over said rims.

In testimony whereof I affix my signature.
HANS C. BEHR.
